RECOVERY OF AROMATICS FROM WATER-CONTAINING CRACKED GAS MIXTURES

Thurman J. Dupy, Port Arthur, Tex., assignor to Gulf Oil Corporation, Pittsburgh, Pa., a corporation of Pennsylvania

Filed July 29, 1957, Ser. No. 674,890

6 Claims. (Cl. 260—674)

This invention relates to a process for recovering organic material and particularly to a process for recovering aromatics from a cracked gas mixture.

It is customary to subject a gas or gaseous mixture, such as ethane, propane and/or butane to cracking conditions in order to obtain a mixture containing gases such as ethylene, propylene, etc. These gases are recovered from these mixtures and employed in many chemical reactions. Included in the cracked gas mixture are aromatics which would also form a desirable product from the cracking reaction. The recovery of aromatics from such mixture is exceedingly difficult, however. Initially, the cracked gas mixture obtained is cooled from a temperature of about 1400° to about 1550° F. to a temperature of about 50° to about 400° F. by contacting the same with cooling water. The cracked gases are easily recovered, thereafter, but the water used in cooling the gases combines with the aromatics present and forms an emulsion therewith. Separation of the aromatics from the resulting emulsion is an exceedingly difficult problem, and as a result thereof much of the aromatics obtained in the cracking reaction is lost.

I have found that the recovery of aromatics from such emulsions can be effected by the expedient of adding an alkaline agent to such emulsion to break the same and obtain a separation of water and aromatics. The water and aromatics can then be separately recovered.

A preferred method of carrying out the invention can be illustrated by reference to the single drawing which describes a flow diagram of such preferred procedure. The drawing is hereby incorporated in and made a part of this specification. In order to simplify the description of the process, flow devices such as valves, etc., have not been shown.

The gases to be cracked, ethane, propane, and/or butane, for example, are introduced into the system by line 2, preferably at a temperature of about 100° to 300° F. Prior to introducing the gases into cracking heater 4, they are joined by steam in line 6 for the purpose of controlling the space velocity of the gases through cracking heater 4 and to inhibit coking. The amount of steam which can be used can be about 10 to about 100 percent by volume based on the gases introduced in line 2. The gases are then passed through cracking heater 4 at a space velocity of about 4,000 to about 14,000 pounds per square foot per hour for about 0.005 to about 0.025 minute. A temperature of about 1400° to about 1550° F. is maintained in cracking heater 4 by means not shown, and the pressure can be from about atmospheric to about 50 pounds per square inch gauge.

As a result of the cracking conditions maintained within cracking heater 4, a cracked gas mixture is obtained containing C₁ to C₆ hydrocarbons, saturated as well as unsaturated, water or steam, hydrogen, carbon dioxide and aromatics comprising benzene, toluene, xylene and tars. The aromatics comprise about 0.1 to about one percent by volume of the cracked gas mixture.

The cracked gas mixture described above is removed

from cracking heater 4 by line 8 and introduced into quench tower 10 wherein it is cooled by cooling water, in the form of a spray, which is introduced therein by one or more lines 12. The cooling water can be at a temperature of about 40° to about 250° F. About 10 to about 30 parts of water per part of gas is sufficient to effect the desired cooling. In order to inhibit secondary reactions from arising within the cracked gas mixture, it is important that the cooling be effected in less than about one second.

Under the conditions existing in the quench tower, the hydrocarbons, hydrogen and carbon monoxide are cooled to a temperature of about 50° to about 300° F. and removed overhead by line 14 for subsequent use. The cooling water and aromatics remaining in quench tower 10 are found in the form of an emulsion and are removed therefrom by line 16 at a temperature of about 100° to about 400° F. The emulsion has a pH of about 2 to about 6.8, generally about 3 to 4. The aromatics present constitute about 0.01 to about 10 percent by weight of the emulsion.

The aromatics present in the emulsion removed from quench tower are valuable commercially. However, great difficulty has been experienced in recovering such aromatics from the emulsion. In accordance with the process of this invention, an alkaline agent which will not adversely affect the aromatics present is added thereto in an amount sufficient to raise the pH of such emulsion to about 7.1 to about 12, preferably about 9 to 10. This is effective in breaking the emulsion and obtaining a separation of water and aromatics. The amount of alkaline agent needed is that required to obtain a pH in the resultant solution as described above. Generally about 0.05 to about 5.0, preferably about 0.1 to about one, percent by weight of alkaline agent relative to the emulsion is effective for such purpose. Temperature of treatment is not critical and can be from about 100° to about 400° F. As alkaline agent any such agent can be used which will produce the desired pH in the resultant mixture without adversely affecting the aromatics present. Thus such alkaline agents as sodium hydroxide, potassium hydroxide, calcium hydroxide, ammonium hydroxide, ammonia, calcium carbonate, sodium carbonate, sodium bicarbonate, potassium bicarbonate, etc. can effectively be used.

In accordance with the above, therefore, the emulsion is introduced into water settler and separator 18 by line 16 and the alkaline agent by line 20. The alkaline agent and emulsion can be mixed in water settler and separator 18 by any convenient means. A contact time of about 1 minute to about 11 minutes is sufficient to obtain the desired pH and resultant separation. Upon breaking of the emulsion, it stratifies into an upper aromatic layer and a lower aqueous layer. The latter is removed from water settler and separator 18 by line 22 and the aromatic layer by line 24. The water removed by line 22 can be recycled to constitute the cooling water used in line 12. The composition of the aromatic fraction removed by line 24 can have the following specification:

	Percent by weight
Olefins	About 2 to about 10
Benzene	About 25 to about 35
Toluene	About 15 to about 25
Xylene	About 2 to about 10
Tars	About 2 to about 10
Water	About 1 to about 5

Further separation of the aromatic fraction into its individual components can be effected in any desired or conventional manner.

The invention can further be illustrated by reference to the following examples.

Example I

22,000 pounds of ethane, 64,000 pounds of propane and 16,000 pounds of butane per hour were introduced along with 42,000 pounds of steam at 240 pounds per square inch gauge and 500° F. into a cracking heater and cracked at temperatures of 1475° to 1520° F. and 10 pounds per square inch gauge to obtain 102,000 pounds of gases comprising C₁ to C₆ saturated and unsaturated hydrocarbons, carbon dioxide, hydrogen and 0.3 percent by volume of aromatics comprising benzene, toluene and tars. The cracked gas mixture was passed to a quench tower where it was contacted with 4290 gallons of water having a temperature of 85° F. The gases were cooled to a temperature of 95° F. and removed overhead from the quench tower. The water and aromatics formed an emulsion having a temperature of 175° F. The aromatics formed 0.047 percent by weight of the emulsion. The emulsion having a pH of 3.5, was passed to a settler and allowed to stand for 11 minutes. There was no indication that a separation of water and aromatics had or would take place. Similar results were obtained with other emulsions of the same character having pH's of 3.5, 3.8, 4.0 and 4.3.

Example II

A run similar to the above was made except that 0.003 percent by weight of a solution containing 5 percent by weight of sodium carbonate and 3 percent by weight of sodium hydroxide was added to the emulsion and the resulting solution, having a pH of 8.0, was permitted to stand 11 minutes. A clean separation of aromatics and water was obtained. Similar satisfactory results were obtained when the same alkaline solution was added to the emulsion to obtain resulting mixtures having pH's of 7.2, 8.4, 9.1, 9.2, 9.8 and 10.0.

Obviously, many modifications and variations of the invention, as hereinabove set forth, can be made without departing from the spirit and scope thereof, and therefore only such limitations should be imposed as are indicated in the appended claims.

I claim:

1. In a process for recovering aromatics from a cracked gas mixture containing the same wherein a hydrocarbon is subjected to cracking conditions to obtain a cracked gas mixture containing gases and aromatics, the cracked gas mixture is cooled by direct contact with water, the gases are separated from said cooled cracked gas mixture, the pH of said cooled cracked gas mixture being from about 2 to about 6.8, and aromatics are separated from the resulting cooled cracked gas mixture, the improvement which comprises adding an alkaline agent to said cracked gas mixture to obtain a resulting mixture having a pH of about 7.1 to about 12, whereby the aromatics present in said cooled cracked gas mixture which would not have formed a separate phase in the absence of such addition are thus formed in a separate phase and the recovery thereof thereby facilitated.

2. In a process for recovering aromatics from a cracked gas mixture containing the same wherein a hydrocarbon is subjected to cracking conditions to obtain a cracked gas mixture containing gases and aromatics, the cracked gas mixture is cooled by direct contact with water, the gases are separated from said cooled cracked gas mixture, the pH of said cooled cracked gas mixture being from about 2 to about 6.8, and aromatics are separated from said cooled cracked gas mixture, the improvement which comprises adding an alkaline agent comprising sodium carbonate to said cracked gas mixture to obtain a resulting mixture having a pH of about 7.1 to about 12, whereby the aromatics present in said cooled cracked gas mixture which would not have formed a separate phase in the absence of such addition are thus formed in a separate phase and the recovery thereof thereby facilitated.

3. In a process for recovering aromatics from a cracked gas mixture containing the same wherein a hydrocarbon

is subjected to cracking conditions to obtain a cracked gas mixture containing gases and aromatics, the cracked gas mixture is cooled by direct contact with water, the gases are separated from said cooled cracked gas mixture, the pH of said cooled cracked gas mixture being from about 2 to about 6.8, and aromatics are separated from said cooled cracked gas mixture, the improvement which comprises adding an alkaline agent comprising sodium hydroxide to said cracked gas mixture to obtain a resulting mixture having a pH of about 7.1 to about 12, whereby the aromatics present in said cooled cracked gas mixture which would not have formed a separate phase in the absence of such addition are thus formed in a separate phase and the recovery thereof thereby facilitated.

4. In a process for recovering aromatics from a cracked gas mixture containing the same wherein at least one hydrocarbon selected from the group consisting of ethane, propane and butane is subjected to cracking conditions at a temperature of about 1400° to about 1550° F. and a pressure of about atmospheric to about 50 pounds per square inch to obtain a cracked gas mixture comprising C₁ to C₆ saturated and unsaturated hydrocarbons, water, carbon dioxide, hydrogen and aromatics, the cracked gas mixture is cooled by direct contact with water in less than about one second to a temperature of about 50° to about 400° F., said C₁ to C₆ hydrocarbons, carbon dioxide and hydrogen are separated from said cooled cracked gas mixture, the pH of said cooled cracked gas mixture being from about 2 to about 6.8, and aromatics are separated from the resulting cooled cracked gas mixture, the improvement which comprises adding an alkaline agent to said cracked gas mixture to obtain a resulting mixture having a pH of about 7.1 to about 12, whereby the aromatics present in said cooled cracked gas mixture which would not have formed a separate phase in the absence of such addition are thus formed in a separate phase and the recovery thereof thereby facilitated.

5. In a process for recovering aromatics from a cracked gas mixture containing the same wherein at least one hydrocarbon selected from the group consisting of ethane, propane and butane is subjected to cracking conditions at a temperature of about 1400° to about 1550° F. and a pressure of about atmospheric to about 50 pounds per square inch to obtain a cracked gas mixture comprising C₁ to C₆ saturated and unsaturated hydrocarbons, water, carbon dioxide, hydrogen and aromatics, the cracked gas mixture is cooled by direct contact with water in less than about one second to a temperature of about 50° to about 400° F., said C₁ to C₆ hydrocarbons, carbon dioxide and hydrogen are separated from said cooled cracked gas mixture, the pH of said cooled cracked gas mixture being from about 2 to about 6.8, and aromatics are separated from the resulting cooled cracked gas mixture, the improvement which comprises adding an alkaline agent comprising sodium carbonate to said cracked gas mixture to obtain a resulting mixture having a pH of about 7.1 to about 12, whereby the aromatics present in said cooled cracked gas mixture which would not have formed a separate phase in the absence of such addition are thus formed in a separate phase and the recovery thereof thereby facilitated.

6. In a process for recovering aromatics from a cracked gas mixture containing the same wherein at least one hydrocarbon selected from the group consisting of ethane, propane and butane is subjected to cracking conditions at a temperature of about 1400° to about 1550° F. and a pressure of about atmospheric to about 50 pounds per square inch to obtain a cracked gas mixture comprising C₁ to C₆ saturated and unsaturated hydrocarbons, water, carbon dioxide, hydrogen and aromatics, the cracked gas mixture is cooled by direct contact with water in less than about one second to a temperature of about 50° to about 400° F., said C₁ to C₆ hydrocarbons, carbon dioxide and hydrogen are separated from said cooled cracked gas mixture, the pH of said cooled cracked gas

mixture being from about 2 to about 6.8, and aromatics are separated from the resulting cooled cracked gas mixture, the improvement which comprises adding an alkaline agent comprising sodium hydroxide to said cracked gas mixture to obtain a resulting mixture having a pH of about 7.1 to about 12, whereby the aromatics present in said cooled cracked gas mixture which would not have formed a separate phase in the absence of such addition are thus formed in a separate phase and the recovery thereof thereby facilitated.
